Primary Examiner — Jeffrey D Asch*Assistant Examiner* — Rebekah A Caruso(74) *Attorney, Agent, or Firm* — Wagenknecht IP Law Group, PC(57) **CLAIM**

What is claimed is the ornamental design for a two in one connector, as shown and described.

DESCRIPTION

FIG. 1 is a top, front, left perspective view of a two in one connector showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof; wherein the broken lines are for illustrative purposes only and form no part of the claimed design.
